UNITED STATES PATENT OFFICE.

FRANK FETZER MORRISON, OF CHARLOTTE, NORTH CAROLINA.

CRIB.

Application filed February 8, 1926. Serial No. 36,858.

This invention relates to a child's crib, and more especially to that type mounted on small wheels whereby it can be moved from place to place.

It is an object of the present invention to provide a structure of this character which can be folded readily into a compact bundle so as to be easily stored or transported.

A further object is to provide a crib which, when set up for use, will afford protection to the occupant from insects.

With the foregoing and other objects in view which will appear as the description proceeds, the invention resides in the combination and arrangement of parts and in the details of construction hereinafter described and claimed, it being understood that changes in the precise embodiment of the invention may be made within the scope 20 of what is claimed without departing from the spirit of the invention.

In the accompanying drawings the preferred form of the invention has been shown.

25 In said drawings,

Figure 1 is a side elevation of the device, two positions of one of the movable members being indicated by broken lines.

Figure 2 is a top plan view.

30 Figure 3 is a section on line 3—3 of Figure 2.

Figure 4 is a section on line 4—4 Figure 3.

Figure 5 is an enlarged end elevation showing, by broken lines, the positions of the side panels of the crib when properly folded.

Figure 6 is an end view of the folded crib.

40 Referring to the figures by characters of reference 1 designates the bottom of the crib to one side of which is hingedly connected a panel 2, the hinges being indicated at 3.

45 Secured along the opposite side of the bottom 1 is a flange 4 to which are connected hinges 5 which serve to attach a side panel 6 to the flange. The height of the flange 4 is equal to or slightly greater than the thickness of the panel 2. Thus it will be seen that when panel 2 is swung downwardly onto the bottom 1, it is possible to swing the panel 6 inwardly and downwardly onto the panel 2.

50 55 Extending upwardly from the ends of the bottom 1 are end flanges 7 each of which

is equal in height to the combined thicknesses of the two panels 2 and 6. To each of these end flanges is hingedly connected an end panel 8 and after the panels 2 and 6 have been swung inwardly as heretofore explained and as shown particularly in Figure 6, the end panels 8 can be swung downwardly onto the side panels 6, it being understood that these end panels are of a height equal to or less than one-half the length of the bottom. Consequently the panels when folded will form a flat bundle as shown in Figure 6.

All of the panels are so proportioned that, when they are set up for use, their upper edges will occupy the same horizontal plane. These upper edges are designed to support top panels 9 which, when properly positioned on the crib, meet at their inner edges while their opposite end edges are substantially flush with the outer faces of the end panels 8. Panels 9 can be fastened together by any suitable means, such as a hook 10 shown in Figures 1 and 2.

Each of the top panels 9 is connected to one of the end panels 8 by a pair of links 11 which are diagonally disposed when the parts are set up for use and extend across the upper corner portions of the side panels 2 and 6. These links are pivotally connected to the sides of the end panels 8 and of the top panels 9 and serve to hold these panels properly assembled when the top panels 9 are fastened together. The links 11 also prevent the side panels 2 and 6 from swinging laterally from under the top panels it being understood of course that these side panels are prevented from swinging inwardly by the mattress which is placed on the bottom 1 as ordinarily. Links 11 are so proportioned that, when it is desired to collapse the crib, said links can be swung outwardly and downwardly in the direction indicated by the arrow in Figure 1 so as to bring the top panel 9 flat against the outer face of the end panel 8. Thus when these end panels are swung downwardly and inwardly on the side panel 6, the top panels will be positioned flat upon the end panels as shown in Figure 6.

Access can be had readily to the interior of the crib by swinging either or both of the top panels 9 to the position indicated by broken lines in Figure 1.

Hingedly connected to the bottom 1 adjacent the sides thereof are longitudinal strips

12 to the end portions of which are connected the forks 13 of supporting wheels 14. For the purpose of holding these strips 12 against folding while the crib is in use, a bolt 15 can be extended upwardly through each of the strips 12 and through the bottom 1. By tightening this bolt the parts will be properly held together. By removing each bolt the strips 12 can be swung inwardly against the lower surface of the bottom 1 as shown in Figure 6.

It is to be understood that the various panels can be provided with wire netting so as to exclude insects from the crib and afford the desired ventilation.

The crib can be made of any size desired and, when not in use, can be readily folded into a compact bundle as shown in Figure 6 and thus stored in a comparatively small space.

What is claimed is:

A collapsible crib including a bottom,

wheel supported strips hingedly connected thereto and foldable thereagainst, means extending through the bottom and strips for holding them against relative movement, said means being removable, side and end panels hingedly connected to the bottom and foldable relative thereto, top panels adapted to rest upon the side and end panels when set up for use, links constituting the sole connections between the top and end panels, said links being connected to the side edges of the top and end panels to provide abutments for limiting outward swinging movement of the side panels, each top panel, when the crib is folded, being movable to positions flat upon and substantially within the bounds of the end panel to which it is linked.

In testimony that I claim the foregoing as my own, I have hereto affixed my signature.

FRANK FETZER MORRISON.
